UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR UNIT.

1,272,646.

Specification of Letters Patent. Patented July 16, 1918.

Application filed October 10, 1917. Serial No. 195,843.

To all whom it may concern:

Be it known that I, JOHN M. FEDDERS, a citizen of the United States, residing at Buffalo, in the county of Erie and State of New York, have invented new and useful Improvements in Radiator Units, of which the following is a specification.

This invention relates to improvements in the construction of the units which enter 10 into the manufacture of radiators whereby the water circulated in gas engines is reduced in temperature and it has for its object the production of radiating members for such units which can be produced at less 15 cost and still maintain the maximum radiating efficiency of the radiators and also present a cellular appearance of the radiators.

In the accompanying drawings:

Figure 1 is a front elevation, partly in 20 section, of several units of the core of a radiator. Fig. 2 is a horizontal section taken on line 2—2 Fig. 1. Fig. 3 is a fragmentary perspective view of one of the radiating members. Fig. 4 is a similar view of one of 25 the plates forming part of one of the radiating members.

Similar characters of reference indicate corresponding parts throughout the several views.

30 The conduits of the radiator through which the water of the gas engine is passed for cooling the same comprise passages or tubes 1 which are arranged side by side and each of which is preferably constructed of 35 two sheet metal walls 2, 2, which are corrugated so as to produce a tortuous or serpentine passage for the water. These two walls of each water tube are preferably held apart a proper distance by providing their corresponding longitudinal edges with off-sets 40 3, 3 which engage with each other and are connected to form a water tight joint by means of solder or other suitable means.

The opposing walls of adjacent water 45 tubes form the outer walls of a radiator unit between which is arranged a radiating member which divides the space between these outer walls into a plurality of air passages 4, 4 and thereby aids in dissipating the heat 50 of the water passing through the water

tubes. This radiating member forms the subject of the present invention and in its preferred form the same is constructed as follows:

Between the outer walls of each unit and 55 adjacent to opposite longitudinal edges thereof are arranged two end supporting sections each of which comprises a plurality of longitudinal webs 5, and a plurality of 60 pairs of transverse plait 6, 6 which are arranged in a longitudinal row on opposite sides of the webs. The two plies of each plait are connected at their outer edges with each other and engage with the bottom or 65 valley of an adjacent corrugation of the respective outer wall. The inner end of one plait is connected with the inner end of one plait, while the inner end of the other plait is connected with the adjacent side edge of 70 one of the longitudinal webs. The several longitudinal webs and transverse plait are preferably formed of a single sheet of metal in any suitable manner.

Between the end supporting sections of 75 each radiating member and the adjacent outer walls of a radiating unit is arranged a plurality of transverse radiating plates 7 which are constructed of sheet metal. At 80 its opposite ends each of these radiating plates is provided with longitudinal slots or notches 8 extending inwardly from the ends thereof so as to form two end tongues 9, 9 at each end of this plate. In assembling 85 the radiator unit one of the tongues 9 of a pair at each end of the radiating plate is inserted in the seat or space formed between the plies of one plait of a pair on one of the end supporting sections, while the other tongue of this pair engages with the seat or 90 space between the two plies of the companion plait of this end section. In order to stiffen each of these radiating plates and serve as a stop for limiting the entrance of 95 a pair of tongues into the seats of a pair of plait, this plate is provided adjacent to the inner ends of its notches or slits 8 with transverse beads 10 which are adapted to engage the inner sides of the end supporting 100 sections, as best shown in Figs. 2 and 3. By

this means the end sections and plates of each radiating unit can be rapidly assembled and still bring the outer ends of the tongues always flush with the end sections 5 so as to produce a neat and finished appearance.

In order to permit the intermediate portions 11 of the longitudinal edges of the radiating plates to bear against the intermediate 10 parts of the adjacent valleys of the outer walls of the radiating unit, the central part of each of these plates is made sufficiently wide for this purpose but the end portions of these plates are reduced slightly as shown 15 at 12 in Figs. 2 and 4, so as to enable the tongues to engage with the respective pairs of plaits on the end supporting sections.

One end of a pair of outer walls of a radiator unit may be connected by a fold 13 and 20 the opposite ends thereof may be interlocked by means of a seam 14 as shown in Fig. 1. When the several parts of a radiator unit have been thus assembled, they are retained 25 in position relatively to each other by soldering the outer ends of the end sections and radiating plates to each other and to the outer walls of this unit. This solder connection between the several pairs of tube walls and radiating members is preferably 30 effected in the usual and well known manner by dipping opposite sides of the completed radiator core in a bath of solder.

A radiating member for radiator units thus constructed can be produced at comparatively 35 low cost inasmuch as it consumes a minimum amount of metal and yields a maximum radiating efficiency.

I claim as my invention:

1. A radiator unit comprising two outer 40 walls, and an intermediate radiating member comprising end supporting sections arranged lengthwise between said walls at opposite longitudinal edges thereof, and a plurality of transverse plates arranged at intervals 45 between said walls and each supported at its opposite ends on said supporting sections.

2. A radiator unit comprising two outer 50 walls, and an intermediate radiating member comprising end supporting sections arranged lengthwise between said walls at opposite longitudinal edges thereof, and each provided with folded parts forming seats and a plurality of plates arranged at intervals between said walls and each engaging its opposite ends with corresponding seats of said supporting sections.

3. A radiator unit comprising two outer 60 walls, and an intermediate radiating member comprising end supporting sections arranged lengthwise between said walls at opposite longitudinal edges thereof, and each provided with a plurality of longitudinal webs and a plurality of pairs of transverse plaits, one ply of each plait being connected with

one ply of the companion plait and the other 65 ply of each plait being connected with the adjacent web and the spaces between said plaits forming seats, and a plurality of transverse plates arranged between said walls and each engaging its ends with seats 70 of a pair of plaits.

4. A radiator unit comprising two outer walls, and an intermediate radiating member comprising end supporting sections arranged lengthwise between said walls at opposite 75 longitudinal edges thereof and each provided with a plurality of longitudinal webs and a plurality of pairs of transverse plaits, one ply of each plait being connected with one ply of the companion plait and the other 80 ply of each plait being connected with the adjacent web and the spaces between said plaits forming seats, and a plurality of transverse plates arranged between said walls and each plate being provided at each of its ends with a longitudinal slit forming a pair of end tongues which engage respectively with the seats of a pair of said plaits.

5. A radiator unit comprising two outer walls, and an intermediate radiating member 90 comprising end supporting sections arranged lengthwise between said walls at opposite longitudinal edges thereof and each provided with a plurality of longitudinal webs and a plurality of pairs of transverse plaits, 95 one ply of each plait being connected with one ply of the companion plait and the other ply of each plait being connected with the adjacent web and the spaces between said plaits forming seats, and a plurality of transverse plates arranged between said walls and each plate being provided at each of its ends with a longitudinal slit forming a pair of end tongues which engage respectively with the seats of a pair of said plaits, 100 and each plate being also provided with beads engaging with the inner sides of said plaits.

6. A radiator unit comprising two outer walls, and an intermediate radiating member comprising end supporting sections arranged lengthwise between said walls at opposite longitudinal edges thereof, and each provided with a plurality of longitudinal webs and a plurality of pairs of transverse 115 plaits, one ply of each plait being connected with one ply of the companion plait and the other ply of each plait being connected with the adjacent web and the spaces between said plaits forming seats, and a plurality of transverse plates arranged between said walls and each plate being provided at each of its ends with a longitudinal slit forming a pair of end tongues which engage respectively with the seats of a pair of said plaits, 120 and each plate being also provided with beads engaging with the inner sides of said end sections.

7. A radiator unit comprising two outer walls, and an intermediate radiating member comprising end supporting sections arranged lengthwise between said walls at opposite longitudinal edges thereof, and each provided with folded parts forming seats, and a plurality of plates arranged at intervals between said walls and each engaging the central parts of its side edges with said walls while its end portions are reduced in width ¹⁰ and engage with corresponding seats of said end sections.

JOHN M. FEEDERS.
